UNITED STATES PATENT OFFICE.

THOMAS N. RUSSELL, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

RAILWAY-CAR.

1,359,278.

Specification of Letters Patent. Patented Nov. 16, 1920.

Application filed April 14, 1917. Serial No. 162,157.

To all whom it may concern:

Be it known that I, THOMAS N. RUSSELL, a citizen of the United States, and a resident of Chicago, in the county of Cook and State of Illinois, have invented certain new and useful Improvements in Railway-Cars, of which the following is a specification, reference being had to the accompanying drawings.

10 My invention relates to railway cars and it has for its principal object the provision of new and improved car-end structure applicable to a new car in the course of being built or as a repair structure for an old car of

15 either steel frame or wooden frame construction. In order to provide the proper rigidity of the end structure so as to render it capable of taking care of the stresses brought to bear upon it by the often repeated stop-

20 ping and starting of the car, with the attendant shifting of the load or the tendency of the load to shift, I have used end-closure plates reaching from the top of the car to the bottom, such plates being provided with

25 reinforcing ribs pressed in vertical position therein for providing a maximum strength. In order to provide the desired rigidity between the side edges of the car so as to prevent the plates from bowing outward longitudinally of the car, I have provided a flange

30 at the upper end portions of the end-closure plates, such flange standing in horizontal position being adapted to co-operate with the vertical strengthening ribs for reinforcing

35 the car end structure. In addition to the horizontal flange, I have provided longitudinally-extending brace bars which brace the end-closure plates directly from the side plates and which also have a truss bracing

40 effect. By the provision of means for bracing the several plates against bowing outward between the sides of the car and by the use of plates reaching from the top to the bottom of the car, such plates being pro-

45 vided with strengthening ribs, I have provided an end structure capable of resisting enormous stresses and capable of standing the wear and tear of ordinary use to very good advantage. It is another object of my

50 invention to improve end structures for railway cars in sundry details hereinafter pointed out. The preferred means by which I have accomplished my several objects are illustrated in the accompanying drawings

55 and are hereinafter specifically described.

That which I believe to be new and desire to cover by this application is set forth in the claims.

In the drawings:—

Figure 1 is a perspective view showing 80 the end of a car-body embodying my improved construction, the roof of the car being omitted;

Fig. 2 is an enlarged fragmentary view, being a section taken on line 2—2 of Fig. 1; 65

Fig. 3 is an enlarged detail, being a horizontal sectional view taken on line 3—3 of Fig. 1;

Fig. 4 is a plan view showing the arrangement of the means for bracing the upper 70 end of the end structure;

Fig. 5 is an enlarged detail, being a vertical sectional view taken on line 5—5 of Fig. 1;

Fig. 6 is an enlarged detail, being a per- 75 spective view of a gusset-plate by which a pair of longitudinally-extending brace-bars are secured at an angle to each other to the side plate at each side of the car;

Fig. 7 is an end view of a structure simi- 80 lar to that of Fig. 1, but provided with an end-door; and

Fig. 8 is a view similar to Fig. 7, but showing a changed position of the end-door. 85

Referring to Figs. 1 to 6 of the drawings, in which corresponding parts are indicated by the same reference characters,—

15 indicates channel-irons extending longitudinally of the car near its central longitudinal line. Extending transversely of the channel-irons 15 at their ends is an angle-iron 16 (see Fig. 5) to which the side sills 17 and the intermediate sills 18 are secured. Side sheathing boards 19 are 90 secured at their lower ends to the side sills 17 and at their upper ends to side plates 20 which are suitably supported in position relative to the side sills 17. Suitable flooring boards 21 are secured in position upon 100 the sills 17—18 as will be readily understood.

The end-closure means for the car comprises two sheet metal plates 22—23 arranged side by side and secured together at 105 their adjacent edges by means of a series of rivets 24. The end-closure plates 22—23 are secured to the angle-iron 16 by means of a series of rivets 25, and are secured to the sides of the car by means of suitable 110

bolts 26 passing through flanges 27 formed at the outer edge portions of said plates. The plates 22-23 are provided with vertically-extending strengthening ribs 28
5 pressed therein, in the construction shown being pressed inward from the normal plane of the end-closure plate, as best seen by an inspection of Fig. 3.

At their upper end portions the plates
10 22-23 are provided with horizontally-turned angles 29 upon which are secured the ridge-pole 30 and purlins 31 by which the roof structure for the car is supported. By reason of the flanges 29 being horizontally
15 disposed, such flanges are adapted to brace the end-closure plates against bowing outward between the sides of the car, and are adapted in coöperation with the strengthening ribs 28 of the end-closure plates to
20 render the end structure very strong so as to be capable of efficiently resisting the heavy stresses brought to bear thereon.

For further bracing the end-closure plates against bowing outward longitudinally of
25 the car, I have provided longitudinally-extending brace-bars 32 and 33 at each side of the car, such brace-bars being secured at their forward ends to the side plates 20 of the car by means of gussets 34. The gussets
30 34 are secured in position by means of vertically extending bolts 35 extending downward through the side plates 20 and also by means of bolts 36 extending through the side plates 20 and through suitable vertical
35 flanges 37 of said gussets. Each of the longitudinally-extending bars 32-33 is suitably secured by means of bolts or rivets to the flange 29 of the end-closure plate at that side of the car as is best shown in Fig.
40 4. By reason of the triangular arrangement of the bars 32 and 33 relative to the flange 29, a virtual truss effect is attained, serving to render the bracing through the bars 32-33 very effective.

45 As is best shown in Figs. 1 and 5, a striking casting 38 is connected to the ends of the channel-irons 15 and to the lower ends of the end-closure plates 22-23. A coupler 39 of any suitable type has its shank portions supported by an angle-bar 40 extending transversely of the striking casting at its lowermost portion.

In Figs. 7 and 8, which show modified forms of construction, parts which correspond to the showing of Figs. 1 to 6 are indicated by the same reference characters, but with the addition of exponents *a* and *b*, respectively. In the construction shown in Fig. 7 a door 41 is provided covering a door
60 opening 42 cut in the adjacent edges of the end-closure plates 22^a-23^a near the lower edge of the plates, the inner two vertical strengthening ribs 28^a being faded out a short distance above the door opening. In

the construction shown in Fig. 8, a door 43 is provided covering an opening 44 in the adjacent edges of the end-closure plates 22^b-23^b near the upper edge of said plates, the inner two strengthening ribs 28^b being faded out near the lower edge of the opening 44.

By the use of my improved arrangement of parts, employing vertically-extending strengthening ribs pressed in the end-closure plates, a very strong reinforcement is secured against the action of a shifting load.
75 By reason of the strengthening ribs 28 being arranged relative to the bracing and strengthening means at the top of the end-closure structure in such a manner as to provide a mutual reinforcement, and further by reason of the fact that the ribs 28 extend vertically, the strength of the entire number of ribs is brought to bear upon the load regardless of the height or level in the car
80 to which the load extends. The car is therefore peculiarly adapted for use with any type of shifting load whether such load be of exceedingly heavy material and extend upward only a short distance above the floor
85 or of comparatively light material and extend upward substantially to the roof.

What I claim as my invention and desire to secure by Letters Patent, is—

1. In a railway car, the combination of
95 an end-closure plate having a plurality of strengthening ribs pressed in vertical position therein, and a door closing an opening in said plate, one or more of the vertical strengthening ribs being faded out adjacent to the edge of the door opening while the remaining vertical strengthening ribs extend substantially to the edge of the end-closure plate.

2. In a railway car, the combination of a
100 plurality of end-closure plates arranged side by side transversely of the car and each having a plurality of strengthening ribs pressed in vertical position therein, means for connecting said end-closure plates together at their adjacent edges, and a door closing an opening in two adjacent plates, two adjacent strengthening ribs being faded out adjacent to the edge of the door opening while the remaining vertical strengthening ribs extend substantially to the edge of the end-closure plates.
110

3. In a railway car, the combination of
115 an end-closure plate having a plurality of strengthening ribs pressed in vertical position extending substantially from the upper edge of said plate to the lower edge thereof, and a door closing an opening cut out of one side edge of said end-closure plate, said plate being provided with a
120 shorter vertical strengthening rib extending substantially from the edge of said opening to the opposite edge of the plate.

4. In a railway car, the combination of a plurality of end-closure plates arranged side by side transversely of the car and each having a plurality of strengthening ribs 5 pressed in vertical position therein extending substantially from the upper edge of the plate to the lower edge thereof, means for connecting the adjacent edges of said plates together, and a door closing an opening cut out of the adjacent side edges of two of said 10 plates between the vertical strengthening ribs therein, each of said plates being provided also with a shorter vertical strengthening rib extending substantially from the edge of said opening to the opposite edge 15 of the plate.

THOMAS N. RUSSELL
